FIREARM BOLT STOP

Grant Hammond, West Haven, Conn., assignor
to Auto-Ordnance Corporation, Bridgeport,
Conn., a corporation of New York

Application August 26, 1941, Serial No. 408,286

3 Claims.

(Cl. 42—18)

This invention relates to an improvement in automatic firearms of the type shown in my co-pending application Serial No. 405,971, filed August 8, 1941.

The object of this invention is to provide a firearm of the above-mentioned type wherein the bolt is held positively in the retracted position after the last cartridge is fired and may be released by hand after the empty magazine has been replaced by a full magazine.

In one aspect the present invention involves a bolt stop movably mounted in the receiver of a firearm to move between an operative position in which it holds the bolt in retracted position after the last cartridge is fired and an inoperative position in which the bolt is free to reciprocate back and forth, the bolt stop being disposed in the receiver and the bolt having a groove along one side to accommodate the bolt stop when the latter is in inoperative position. In another aspect the invention involves a magazine having a follower for moving the cartridges in front of the bolt and an actuator for moving the bolt stop into operative position, together with a spring for moving the follower relatively to the magazine and moving the actuator relatively to the follower. Other aspects will be evident from the illustrative embodiment of the invention shown in the accompanying drawing, in which

Fig. 1 is a side elevation of a firearm embodying this invention, a part of the magazine being broken away;

Fig. 2 is an enlarged sectional view taken along the line 2—2 in Fig. 1 with the magazine partly full;

Fig. 3 is a view similar to Fig. 2 of an empty magazine;

Fig. 4 is a left side view of the bolt, bolt stop and magazine with parts of the magazine broken away and the bolt in the advanced position; and

Fig. 5 is a view similar to Fig. 4 with the magazine empty and the bolt locked in the retracted position.

The illustrated firearm comprises a stock S, a barrel BL, a trigger T, a receiver R, a bolt B, a bolt stop BS, a bolt actuator BA, and a magazine M.

The bolt B is cylindrical in contour and reciprocates back and forth in the receiver R. In its forward position (see Fig. 4) the bolt is over the magazine M. The magazine is mounted in an opening at the under side of the firearm and the bolt B is provided with recesses 18 which accommodate the lips of the magazine. The bolt B is also provided with a recess 19 which accommo-

dates the bolt stop BS, as will be pointed out below.

The magazine M is removably secured in the opening of the firearm by a catch 65 which enters a notch 64 formed in the magazine wall.

As shown in the drawing, the magazine is of the box type, being provided with a spring-pressed follower 66 by which the uppermost cartridge is urged into position in front of the bolt when retracted. Near the upper end of the left side of the magazine is an opening 67 and pivotally mounted on the bottom of the follower 66 by means of a pivot pin 68 is a bolt-stop actuator 69 having a nose 70 adapted to be projected through the opening 67 when the magazine becomes empty. Normally the actuator 69 extends obliquely to the side walls of the magazine and the follower spring 71 tends not only to lift the follower 66 but also to swing the actuator 69 about its pivot 68 so that its nose 70 passes through the opening 67 as the follower passes above it.

The bolt stop BS comprises a thin elongate strip pivotally mounted on the inner face of the left side of the receiver R by means of a pin 72 at its forward end. Intermediate its ends the bolt stop is provided with a depending portion 73 which is adapted to be engaged by the nose 70 of the actuator 69 when the magazine is empty. The bolt stop is normally so positioned that it lies in the recess 19 of the bolt B and permits the free reciprocation thereof. When, however, the bolt stop BS is raised by the engagement of the nose 70 of the actuator 69 with the portion 73 (see Fig. 5), its rearward end 74 enters the path of the bolt and prevents forward movement of the bolt at the completion of its recoil movement. A handle 75 attached to the bolt stop and extending outwardly through a slot in the receiver R limits the downward movement of the bolt stop and permits its manual operation.

It should be understood that the present disclosure is for the purpose of illustration only and that this invention includes all modifications and equivalents which fall within the scope of the appended claims.

I claim:

1. In a firearm having a receiver, a bolt reciprocable therein and a magazine by which cartridges are fed, a bolt stop, and an actuator carried by the magazine which actuates the bolt stop when the magazine becomes empty, said magazine having an opening in its side wall adjacent the mouth of the magazine and including a follower on which the cartridges rest and to

which the actuator is pivotally secured, and a spring by which the follower is advanced to feed the cartridges and by which the actuator is swung on its pivot to cause the nose of the actuator to pass through said opening when the last cartridge is fed from the magazine.

2. In a firearm having a receiver, a bolt reciprocable therein and a magazine by which cartridges are fed, a bolt stop, and an actuator carried by the magazine which actuates the bolt stop when the magazine becomes empty, said bolt stop being pivotally mounted upon said receiver adjacent the mouth of the magazine, a follower in the magazine, said actuator being pivotally mounted on the follower within said magazine, said magazine having an opening in the side wall thereof adjacent its mouth, and beneath said bolt stop, and a spring within said magazine by which the follower is advanced to feed the cartridges and by which the actuator is swung on

its pivot to pass its nose through said opening into actuating engagement with said bolt stop.

3. In a firearm having a receiver, a bolt reciprocable therein and a magazine by which cartridges are fed, a bolt stop, and an actuator carried by the magazine which actuates the bolt stop when the magazine becomes empty, said bolt stop being pivotally mounted upon said receiver adjacent the mouth of the magazine and said magazine having an opening in the side wall thereof adjacent its mouth and including a follower on which the cartridges rest and to the under face of which said actuator is pivotally secured, and a spring by which said follower is advanced and said actuator swung on its pivot to pass the nose of the actuator through said opening into actuating engagement with said bolt stop.

GRANT HAMMOND.
